UNITED STATES PATENT OFFICE.

CHARLES H. WILLSON, OF MEDFORD, ASSIGNOR TO JAMES W. BROOKS, OF PETERSHAM, AND FRANK F. STANLEY, OF SWAMPSCOTT, MASSACHUSETTS, TRUSTEES.

DESIGN FOR A NAIL OR SLUG.

SPECIFICATION forming part of Design No. 25,083, dated January 21, 1896.

Application filed December 18, 1895. Serial No. 572,606. Term of patent 31 years.

To all whom it may concern:

Be it known that I, CHARLES H. WILLSON, of Medford, county of Middlesex, and State of Massachusetts, have invented and produced 5 a certain new and useful Design for a Nail or Slug, of which the following is a specification, reference being had to the accompanying drawings, forming a part thereof.

Figure 1 of the drawings is an isometric 10 view of a nail or slug, illustrating my design; and Fig. 2 is an end view thereof.

The leading feature of my design consists in two longitudinal grooves in each side of a nail or slug, oppositely located, dividing it 15 into three cylindrical portions of different diameters, connected by thinner necks or fins, and with their longitudinal axes in the same plane.

As shown in the drawings, the nail or slug is grooved longitudinally at *a* and *b*, *a'* and *b'*, two grooves on each side, dividing it into three cylindrical portions *c*, *d* and *e*, of gradually-decreasing diameters, connected by thin necks or fins *a^x* and *b^x*, the longitudinal axes of the cylindrical portions lying in the same 25 plane.

I claim—

The design for a nail or slug, substantially as set forth.

In testimony whereof I have signed my 30 name to this specification in the presence of two subscribing witnesses.

CHARLES H. WILLSON.

Witnesses:

JOHN C. EDWARDS,
FREDERICK L. EMERY.
